UNITED STATES PATENT OFFICE.

ORVEL L. ELLIS, OF PITTSBURG, TEXAS.

RAIL-JOINT.

1,200,093.

Specification of Letters Patent.

Patented Oct. 3, 1916.

Application filed April 15, 1916. Serial No. 91,362.

To all whom it may concern:

Be it known that I, ORVEL L. ELLIS, a citizen of the United States, residing at Pittsburg, in the county of Camp and State 5 of Texas, have invented certain new and useful Improvements in Rail-Joints, of which the following is a specification, reference being had to the accompanying drawings.

10 This invention relates to certain improvements in rail joints and it is an object of the invention to provide a device of this general character wherein the meeting ends of rails are effectively and conveniently maintained 15 in assembled relation.

The invention consists in the details of construction and in the combination and arrangement of the several parts of my improved rail joint whereby certain important 20 advantages are attained and the device is rendered simpler, less expensive and otherwise more convenient and advantageous for use, all as will be hereinafter more fully set forth.

25 The novel features of the invention will hereinafter be definitely claimed.

In order that my invention may be the better understood, I will now proceed to describe the same with reference to the accompanying drawings, wherein—

Figure 1 is an elevational view illustrating a rail joint constructed in accordance with an embodiment of my invention; Fig. 2 is a view partly in elevation and partly in section illustrating certain details of the invention as herein embodied; and Fig. 3 is a sectional view taken substantially on the line 3—3 of Fig. 2.

As disclosed in the accompanying drawings, 1—1 denote the meeting ends of rails having their under surfaces at predetermined points inwardly of their free ends provided with the recesses or sockets 2 for a purpose to be hereinafter more particularly referred to.

3 denotes a plate upon which the meeting ends of the rails are adapted to rest and the longitudinal marginal portions of said plate 3 are provided with the upstanding flanges 4 adapted to overlie the flanges 5 of the rails and to snugly engage the webs 6 thereof, and it is to be observed that the flanges 3 have their lower marginal portions 7 substantially vertical and the upper marginal portions 55 thereof inclined inwardly as this arrange-

ment has been found to afford a maximum of efficiency.

The under surface of the plate 3 is provided with a longitudinally disposed groove 8 terminating in the openings 9 adapted to register with the recesses or sockets 2 hereinbefore referred to.

10 denotes a clamping member formed of metal and substantially U-shape in form and adapted to be seated within the elongated 65 groove 8 with the stems 11 thereof disposed through the openings 9 and extending within the registering recesses or sockets 2, whereby the meeting ends of the rails are effectively held against separation. The stems 70

11 are resilient and are normally disposed in upward converging planes whereby they are caused to positively contact with the beveled outer walls of the recesses or sockets 2 whereby the clamping member 10 is effectively 75 maintained in operative position relative to the rails 1 and the plate 3. It will also be understood that the resiliency of the stems 11 will compensate for the expansion or contraction of the rails 1 incident to the elements. It will also be understood that the clamping member 10 may be further held in applied position by positioning the plate 3 upon a tie.

From the foregoing description, it is 85 thought to be obvious that a rail joint constructed in accordance with my invention is of an extremely simple and comparatively inexpensive nature and is particularly well adapted for use by reason of the convenience 90 and facility with which it may be assembled, and it will also be obvious that my invention is susceptible of some change and modification without material departure from the principles and spirit thereof and for this 95 reason I do not wish to be understood as limiting myself to the precise arrangement and formation of the several parts herein shown in carrying out my invention in practice.

I claim:

1. In combination with the meeting ends of rails provided with sockets in their under surfaces, a plate underlying the rails and provided with upstanding flanges adapted 105 to coact with the flanges and webs of the rails, said plate being provided with openings adapted to register with the sockets in the rails, and a clamping member substantially U-shape in form, the stems thereof 110

being insertible through the openings in the plate and within the sockets of the rails when in register with said openings.

2. In combination with the meeting ends 5 of rails provided with sockets in their under surfaces, a plate underlying the rails and provided with upstanding flanges adapted to coat with the flanges and webs of the rails, said plate being provided with openings adapted to register with the sockets in the rails, and a clamping member substantially U-shape in form, the stems thereof being insertible through the openings in the

plate and within the sockets of the rails when in register with said openings, the under surface of the plate intermediate the openings being grooved, the intermediate portion of the clamping member being seatable within said groove. 15

In testimony whereof I hereunto affix my 20 signature in the presence of two witnesses.

ORVEL L. ELLIS.

Witnesses:

C. J. ELLIS,
J. E. CANTWELL.
